United States Patent Office.

JUSTUS E. ZENDER, OF NEW YORK, N. Y.

Letters Patent No. 70,932, dated November 12, 1867.

IMPROVEMENT IN DICE-BOXES.

The Schedule referred to in these Letters Patent and making part of the same.

TO ALL WHOM IT MAY CONCERN:

Be it known that I, JUSTUS E. ZENDER, of the city, county, and State of New York, have invented a new and improved Hand Dice-Box; and I do hereby declare that the following is a full, clear, and exact description thereof, which will enable those skilled in the art to make and use the same, reference being had to the accompanying drawing, forming part of this specification.

The present invention consists, first, in making a hand dice-box of metal, of any suitable nature or kind, as, for instance, of silver, copper, brass, &c., whereby strength and stiffness are imparted thereto, without any increase in bulk or weight over the ordinary paste or card-board and leather boxes of a similar class, and a much more durable and desirable article produced; second, in lining or covering the interior or inside of a dice-box, whether made of metal, as above stated, or in the ordinary or in any other manner, with a layer or layers of felt cloth, whether cotton or wool, or wool and cotton combined, or any other fabric which will cause the sound of the dice, as they are rattled or shaken in the box, to be so deadened or so softened as to produce or occasion but little if any noise, thus overcoming the heretofore disagreeable rattle to the dice in the box—a feature of much importance and advantage.

In the accompanying plate of drawings my improved hand dice-box is illustrated, the figure being a central vertical section through the dice-box.

A, in the drawings, represents my improved dice-box, which I make of metal, either silver, brass, copper, or any other suitable kind, and in any desired shape or style adapted to the purpose of shaking dice. B, a lining or coating of cloth, felt, or other similar material, to and upon the inside of the box A, where it may be secured by cement, glue, or any other suitable adhesive material, or in any other proper manner; the object of this lining B, as well as that for making the box of metal, having been hereinabove stated, and therefore needing no further mention.

What I claim as new, and desire to secure by Letters Patent, is—

1. As a new article of manufacture, a hand dice-box made of metal, substantially as and for the purpose described.
2. I also claim a hand dice-box lined with cloth, or any equivalent material therefor, whether such dice-box be made of metal or any other suitable material, substantially as and for the purpose specified.

The above specification of my invention signed by me this 23d day of April, 1867.

JUSTUS E. ZENDER.
